UNITED STATES PATENT OFFICE.

JOSEPH L. DEVON, OF ATLANTA, GEORGIA.

ROTARY GEAR PUMP.

Application filed February 14, 1925. Serial No. 9,269.

To all whom it may concern:

Be it known that I, JOSEPH L. DEVON, a citizen of the United States, residing at Atlanta, in the county of Fulton and State 5 of Georgia, have invented new and useful Improvements in Rotary Gear Pumps, of which the following is a specification.

The object of my said invention is to improve the waterdrawing ability of rotary 10 gear pumps by the provision in combination with the idler or driven gear of such a pump of any appropriate braking attachment calculated to retard and prevent too free turning of said idler or driven gear, 15 and in that way preclude said gear breaking contact with the driving gear with which it is meshed, such breaking of contact being objectionable because it allows air to slip back from the discharge chamber 20 of the pump to the suction chamber thereof, thereby preventing the pump from developing sufficient vacuum to draw water from overboard suction.

The accompanying drawings show one 25 form or embodiment of my invention capable of carrying out the underlying principles thereof.

In said drawings:—

Figure 1 is a top plan view of a rotary 30 gear pump, mounted on the frame or chassis of a fire-engine automobile or other vehicle.

Figure 2 is a view in end elevation, a portion 35 of the pump being broken away and one of the members of the chassis being shown in section.

Figure 3 is a fragmentary detail view, partly in section and partly in elevation, of part of the braking mechanism.

Figure 4 is a fragmentary view in elevation of the pump with the side removed 40 to show the gears.

Figure 5 is a fragmentary view, in section, on the line 5—5 of Figure 2, the brakeband and operating mechanism therefor being removed; and

Figure 6 is a detail view of the brakeband rocker.

In the drawings, it will be understood 50 that the pump is not shown in detail, only such parts thereof being shown as are necessary to an understanding of my invention.

Referring now in detail, to the drawings:—

1 designates the driving-gear of a rotary

gear pump, such as is used on "fire-engines," so called, of municipal fire departments, and 2 the driven gear thereof, mounted, respectively, on shafts 3 and 4. It will be noted, 60 by reference to Figure 4, that, as customarily constructed, there is a considerable amount of clearance between the meshing teeth, as shown at "A". When drafting water, it is necessary of course, to expel 65 air from the suction pipe and suction chamber, and, sometimes, on a lift of ten feet or more, the pump fails; because, in order to discharge air from the suction faster than it will slip back into it from the discharge 70 chamber, the pump must be run at such speed that the gear-teeth break contact at the point "V", making an opening for air to slip back into the suction from the discharge 75 chamber.

When this form of pump is brand new, the packing 5 is tight enough on the shaft 2 to have the effect of a brake, and so, by preventing this vibration, holds the teeth 80 constantly in contact. However, when this packing becomes a little worn and smooth 85 from wear, it does not grip the shaft so tightly and then driven gear 2 breaks contact with driving gear 1 at the point "V", and the discharge chamber. A braking attachment 90 prevents this, as will be apparent from a reading of the construction and operation thereof, and at this point I desire it distinctly understood that it is within the purview of my invention to employ any type 95 of braking means compatible with the purpose of my invention, the salient feature of which consists in combination with the driving and driven meshed gears of a rotary gear pump, of braking means appropriately applied to the driven or idler gear with a view to retarding the rotation of said gear and thereby averting or preventing breaking of contact between the said gear and the driving gear, for the purpose indicated. 100

To adapt the pump for use in connection with the herein disclosed specific and specifically advantageous braking attachment, which constitutes the subject of my Letters Patent No. 1,461,084, dated July 10, 1923, 105 the driven gear shaft 2 is extended back through the bearing retainer and dust-cap 6, and is provided with an exteriorly projecting reduced end 2'. On said end is mounted a drum 7, around which passes a brakeband 8, the free ends 8' of which are looped around pins 9, passing through four ears 10 ar-

ranged in two pairs, one pair toward each end of a sleeve 11 rotatably mounted on a fulcrum pin 12 secured at one end thereof in bearings 13 detachably secured to one of the 5 cross braces B of the side frame members or channel bars C, of the chassis of the fire-engine. The sleeve 11 and the two pairs of ears 10 form part of a rocker or lever 14 having a web 15, the pin 12 constituting 10 the fulcrum of the lever. The lever resembles somewhat, a bell crank lever of the conventional form, but is a modified and peculiar form thereof. Instead of one short arm, as in the conventional bell crank lever, 15 my lever has two pairs of short arms (the ears 10) and the ears of each pair are connected by pins 9. The lower end of the lever is pivotally secured, as at 16 to a socket member 17, having a screw threaded socket, 20 in which may be screwed a pull-rod 18, having a screw-threaded end 19. The rod projects axially into a tubular member 20, having a pair of lateral arms 21 projecting through registering slots 22, 23 in one of 25 the channel bars C and a wear plate 24, respectively. The wear plate is disposed exteriorly of the channel bar C (as shown in Figure 2,) and suitably secured thereto.

A cam lever 25 is fulcrumed on a pin 26 30 projecting through the lever and through the arms 21, and has the curved cam face 27 bearing against the wear plate 24.

The tubular member 20 may work in the cylindrical bore of a guide member 28.

The guide member 28 and the wear plate 24 are secured to the channel bar C, preferably by common means, such as screws 29.

One of the open ends of the tubular member 20 is exteriorly threaded and a screw closure cap 30 is screwed on such threaded end and is provided with a central aperture through which the pull-rod 18 projects.

The end of the pull-rod 18 within the tubular member 20 is provided with a disk head 31, against which one end of a coiled spring 32 bears, the other end of said spring bearing against the cap 30. The spring encircles the rod 18 as shown.

It will be noted that the attachment or 50 braking device described is very simple and compact and that in operation, by pulling down the lever 25, the brake band 8 is

tightened around the drum 7, thereby braking the shaft 4 of the driven gear 2. It will be noted furthermore that in the operation 55 of the lever 25, it does not pull directly on the rod 18, but on the spring 32, thereby insuring uniform pressure on the brake drum. The lever 25 may be conveniently operated by a fireman standing on the 60 ground beside the fire-engine, the fireman pulling the lever to apply the brake until the pump is primed and the water is being discharged. The brake has then served its purpose and should be thereupon released 65 to prevent wear on the brake band and drum.

Having thus fully described my invention, the many advantages thereof will be apparent, especially to those skilled in the art to which it pertains. It is obvious that 70 many mechanical changes especially in detail, may be made in the particular form of device disclosed but such changes do not necessarily depart from the spirit of the invention or sacrifice any of its advantages 75 and all such as come within the terms of the appended claims fall within the purview of the invention.

Having described my invention, what I claim and desire to secure by Letters-Patent, 80 is:—

1. A rotary gear pump having driving and driven meshed gears, and brake means for cooperation with the driven gear for the retardation of said gear with a view to 85 averting breaking of contact between said gear and the driving gear.

2. A rotary gear pump having driving and driven meshed gears, and braking means for cooperation with the driven gear for the retardation of said gear with a view to 90 averting breaking of contact between said gear and the driving gear, the said braking means being operative-controlled.

3. A rotary gear pump having driving and 95 driven meshed gears, a frame, a rotating shaft fixed to the driven gear, and an operative controlled brake for said shaft.

4. The combination with the driving and driven meshed gears of a rotary gear pump, 100 of a braking attachment for cooperation with the driven gear.

In testimony whereof I affix my signature.
JOSEPH L. DEVON.
